UNITED STATES PATENT OFFICE.

WILLIAM H. GAUSEWITZ, OF MINNEAPOLIS, MINNESOTA, AND HOWARD B. CUMMINGS, OF PRESCOTT, WISCONSIN; SAID CUMMINGS ASSIGNOR TO SAID GAUSEWITZ.

CLOSET.

1,383,295.

Specification of Letters Patent.

Patented July 5, 1921.

Application filed August 27, 1919. Serial No. 320,119.

To all whom it may concern:

Be it known that we, WILLIAM H. GAUSEWITZ and HOWARD B. CUMMINGS, citizens of the United States, residing at Minneapolis, Hennepin county, Minnesota, and Prescott, Pierce county, Wisconsin, respectively, have invented certain new and useful Improvements in Closets; and we do hereby declare the following to be a full, 10 clear, and exact description of the invention, such as will enable others skilled in the art to which it appertains to make and use the same.

Our invention relates to improvements in 15 closets, of the type commonly called dry closets, in which chemicals are placed for well known purposes and which closets are especially adapted for use in localities not provided with sewers. The primary object 20 of our invention is to provide such a closet that may be emptied when filled and the contents thereof conveyed through a conduit to a cesspool, thus eliminating the objectionable feature of the present day dry 25 closet, wherein the receptacle when filled must be carried out and emptied.

To the above end the invention consists 30 of the novel devices and combination of devices hereinafter described and defined in the claims.

In the accompanying drawings, which illustrate the invention, like characters indicate like parts throughout the several views.

35 Referring to the drawings,

Figure 1 is a view in vertical section taken on the line 1—1 of Fig. 2;

Fig. 2 is a transverse vertical section taken on the line 2—2 of Fig. 1;

40 Fig. 3 is a vertical section taken on the line 3—3 of Fig. 2;

Fig. 4 is a view corresponding to Fig. 3 with the exception that the receptacle is turned into an emptying position and with 45 some parts broken away and sectioned; and

Fig. 5 is a fragmentary perspective view of the lock for the receptacle.

The numeral 6 indicates a pair of U-shaped end frames which, as shown, are 50 formed from commercial angle iron. An open top casing 7 is secured to and within the end frames 6 and has its upper marginal edge portion secured to the under side of a seat 8. This seat 8 is supported on and se-

cured to the upper ends of the end frames 55 6 and is provided with a cover 9 hinged thereto, at 10. The front wall of the casing 7 is curved rearwardly and downwardly to the back of the casing and the sides of said casing are made inclined to afford a hopper 60 bottom arranged to empty into a large discharge conduit 11 at the back of the casing 7 and leading to a cesspool, not shown.

A horizontally disposed cylindrical receptacle 12 extends transversely within the casing 7 and has at its ends, a pair of axially aligned trunnions 13 journaled in open seats, formed in bearing plates 14 secured to the inner faces of the ends of the casing 7. In the top of the receptacle 12 is a large opening 15 located directly under the opening in the seat 8 and completely surrounded by a depending endless flange 16 secured to the under side of said seat. The lower edge of the flange 16 is of irregular formation and closely follows the contour of the underlying surface of the receptacle 12. The purpose of the flange 16 is to close the opening between the seat 8 and the receptacle 12.

To lock the receptacle 12 in an upright or 80 filling position, there is provided a forwardly and rearwardly projecting rod 17 turnably mounted in bearings 18 on the under side of the seat 8 and has its rear end bent laterally to form a lock finger 19 arranged to enter a longitudinally extended lock slot 20 in the receptacle 12. The forward end of the rod 17 is bent to form a hand piece 21 by which said rod may be operated to turn the finger 19 into and out 90 of the slot 20.

Within the receptacle 12 is secured a pair of upright agitating blades 22 which are edgewise, spaced longitudinally of said receptacle on opposite sides of the opening 15 95 and slightly rearward of the vertical plane of the trunnions 13. A horizontal and transversely extended cylindrical float 23 is loosely journaled on a horizontal rod 24 which extends axially through said float 100 and its ends are loosely bent around the agitating blades to connect said rod thereto for vertical sliding movement to anchor the float 23 with freedom for vertical movement. Solids striking the float 23 will cause 105 said float to turn on the rod 24 and thereby deposit the load thereon into the liquid in the receptacle 12 to avoid splash.

To empty the contents of the receptacle 12 into the hopper bottom of the casing 7 from where said contents will flow into the discharge conduit 11, there is provided a pair 5 of operating chains 25. These chains 25 are, as shown, secured to the under side of the receptacle 12, extend upward on opposite sides thereof and through apertures in the seat 8 and have attached to their upper ends hand pieces 26. These hand pieces 26 normally engage the top of the seat 8 and support the chains 25 therefrom. By taking hold of the hand pieces 26 and alternately pulling upward on the same, the receptacle 12 may be 10 rocked on its trunnions 13. The rocking of the receptacle together with the agitating blades 22 will loosen the contents of the receptacle 12 and then by a full upward pull on the front chain 25, said receptacle may be 15 turned upside down and the contents thereof emptied into the casing 7. Coöoperating stops 27 and 28 on the casing 7 and receptacle 12, respectively, limit the emptying movement of said receptacle, as shown in Fig. 4. 20 In the seat 8 back of the cover 9, is a bent pipe 29 which may be extended to a chimney or the ventilating stack, not shown.

The float 23 prevents splash, always has a clean side up, for the reason that it is 25 relatively mounted; said float also acts as an indicator to tell when the receptacle 12 is full and should be emptied and it further prevents use of the closet when the receptacle is full, by closing the opening in the seat. 30

What we claim is:—

1. A closet of the kind described comprising a cover-equipped casing, a discharge conduit leading from the casing, a receptacle mounted in the casing for movement to and 40 from an emptying position, and an agitating blade in the receptacle.

2. A closet of the kind described comprising a cover-equipped casing, a discharge conduit leading from the casing, a receptacle mounted in the casing for movement to and 45 from an emptying position, and a float in the receptacle.

3. A closet of the kind described comprising a cover-equipped casing, a discharge conduit leading from the casing, a receptacle 50 mounted in the casing for movement to and from an emptying position, a pair of agitating blades in the receptacle, and a float guided by said blades.

4. A closet of the kind described comprising a cover-equipped casing, a discharge conduit leading from the casing, a receptacle 55 mounted in the casing for turning movement on a horizontal axis to and from an emptying position, a float mounted in the receptacle for turning movement on a horizontal axis, and means for vertically guiding the float.

5. A closet of the kind described comprising a cover-equipped casing, a discharge conduit leading from the casing, a receptacle 60 mounted in the casing for turning movement on a horizontal axis to and from an emptying position, a pair of normally upright agitating blades secured in the receptacle, a 70 horizontal rod secured to the agitating blades with freedom for longitudinal movement thereon, and a float turnably mounted on the rod.

In testimony whereof we affix our signatures in presence of two witnesses.

WILLIAM H. GAUSEWITZ.
HOWARD B. CUMMINGS.
